PEGBOARD MOUNTED SUPPORT FOR DISPLAYING POWER TOOLS

Terrance Neil Touchett, Batavia, and William E. Kotzenberg, Geneva, Ill., assignors to McGraw-Edison Company, Elgin, Ill.

Filed Jan. 16, 1974, Ser. No. 433,704

Term of patent 14 years

Int. Cl. D6—04

U.S. Cl. D6—136

FIG. 1

FIG. 2

FIG. 3

FIG. 4

FIG. 5

FIG. 6

FIG. 7

FIG. 1 is a perspective view of a pegboard mounted support for displaying power tools, showing our new design;

FIG. 2 is a top plan view;

FIG. 3 is a bottom plan view;

FIG. 4 is a side elevational view taken on line 4—4 of FIG. 2;

FIG. 5 is a front elevational view taken on line 5—5 of FIG. 2;

FIG. 6 is a side elevational view taken on line 6—6 of FIG. 2; and

FIG. 7 is a rear elevational view.

We claim:

The ornamental design for the pegboard mounted support for displaying power tools, substantially as shown and described.
